CUSHIONED HARNESS CLAMP

Howard P. Thomas, North Hollywood, Calif., assignor to Thomas Associates, Los Angeles, Calif., a partnership

Application February 14, 1950, Serial No. 144,066

7 Claims. (Cl. 248—74)

1

This invention relates to a cushioned line support of the type known as a harness clamp and which is particularly designed to support a group of electrical conductor wires in aircraft, but may be used for supporting conduit lines or wires in places other than aircraft.

One of the objects of this invention is to provide a cushioned harness clamp of the character described, which is comparatively simple as to construction, may be readily and easily installed and removed, has a comparatively large wire supporting capacity in consideration of its size; holds the wires grouped in small compass, and prevents chafing and wear of and securely holds the wires against derangement and accidental dislodgment from the clamp.

Another object is to provide a clamp such as described, in which the cushioning means thereof is constructed to serve as a separator and closure, for effectively spacing the wires from contact with the structural member to which the clamp is secured and sealing the wires in the clamp. This makes it possible advantageously to form the metal body of the clamp as an open loop, for example of a simple U-shape, whereby the loop has a larger capacity, provides for an easier insertion and removal of the wires, a simplified construction, and a reduced cost of production, compared to harness clamps wherein a metal strap encircles the wires.

A further object is to provide a clamp such as described, wherein a cushioning strip lining the body of the clamp is provided with an extension means for bridging the gap at the open side of the body to space the wires from the structural member on which the clamp is mounted, hold the wires in the clamp and serve as a cushioned seat therefor.

Another object is to provide in a clamp such as described, a cushioning strip having a pair of flap-like extensions adapted to overlap and extend across the open side of the clamp as a closure therefor.

Additionally, it is an object hereof to provide a cushioned clamp such as described, wherein one of the pair of flap-like extensions is considerably thicker than the other and provided with a groove to receive the other extension and hold said extensions against lateral displacement from overlapping and clamp-closing position, thereby

5

more effectively spacing the wires from the structure on which the clamp is mounted, increasing the cushioning action and assuring that the wires will be securely held in place in the clamp.

This invention possesses many other advantages and has other objects which may be made more easily apparent from a consideration of one embodiment of the invention. For this purpose there is shown one form in the drawings accompanying and forming part of the present specification. This form will now be described in detail, illustrating the general principles of the invention; but it is to be understood that this detailed description is not to be taken in a limiting sense, since the scope of the invention is best defined by the appended claims.

Referring to the drawings:

Figure 1 is a perspective view of a cushioned harness clamp embodying the present invention;

20 Figure 2 is a side elevation of the clamp as it would appear when in use, the phantom showing indicating a group of wires or a conduit as supported in the clamp;

Figure 3 is a cross sectional view taken on the line 3—3 of Figure 2;

25 Figure 4 is a vertical section taken on the line 4—4 of Figure 2; and

Figure 5 is a vertical section taken on the line 5—5 of Figure 2.

30 Referring to the drawings more specifically, 6 designates the body member of the clamp which is made of a single piece of somewhat resilient and light strap metal, bent to form an open loop, preferably of a U-shape, and provided with laterally extended and apertured ends forming ears 7 whereby the clamp may be secured to a structural member or support A, as shown in Figure 2, by means of suitable fastenings 8 inserted through said ears.

35 Mounted on the body member 6, as a cushion lining for the inner side thereof, is a cushion strip 9 formed of somewhat soft and resilient rubber or synthetic rubber and held in place by means of rebent marginal flanges 10 formed integral therewith and which embrace the side edges of the body member 6 as plainly shown in Figures 1 and 6. These flanges terminate in closely spaced relation to the ears and make it possible readily to mount and remove the cushion strip, thus facilitating replacement thereof when necessary.

2

In order to effectively close the open side of the clamp for securely holding the wires in place therein, and to provide for spacing the wires as shown in Figure 2 from the structural member on which the clamp is mounted, to prevent chafing and wear of the wires, the cushion strip is provided with extension means which serves these purposes, and preferably, this means is formed integrally with the strip and is subject to free movement into positions for fully opening and closing the clamp.

As here shown the cushion strip 9 has a pair of integral flap-like extensions 11 and 12 at its ends, which are of substantially equal length and extend beyond the ends of the open loop and will substantially bridge the gap between the ends of the clamp when overlapped, thereby providing a full closure for the open side of the clamp as shown in Figure 2. Preferably each extension is of such length as to substantially bridge the gap between the ends of the open loop.

In accordance with the invention, one of the extensions, for example, the extension 12, is of much greater thickness than the extension 11 and is adapted to overlie the latter, thereby considerably spacing the wires from the structural member on which the clamp is mounted and providing a more substantial closure assuring the proper retention of the wires in the clamp as well as forming a better cushioning seat for the wires.

Provision is made for interlocking the extensions 11 and 12 in overlapped relation to prevent relative lateral displacement thereof. As here shown, the extension 12 is formed with a groove 13 extending lengthwise thereof, or in other words is of channeled form, and the extension 11 fits snugly as shown in Figure 4 in the groove or channel 13, thereby preventing relative lateral displacement of the extensions.

As a practicable way of making the extension 12 thicker than extension 11, a separate strip 14 of the cushioning material and of channelled form, is vulcanized to the extension 12 with the latter disposed in the channel thereof, and wherein said channel forms the groove 13. This is shown in Figure 4, it being noted that the channel or groove of the strip 14 is of such depth as to define opposed shoulders 15 which abut the side edges of and positively hold the strip 14 in place. The strip 14 is considerably wider than the strips 11 and 12, and in being vulcanized to strip 12, becomes a part thereof and makes strip 12 in effect wider than strip 11, thus providing a wide seat against the structural member and a more effective spacing and closing action assuring that the wires will be held in the clamp and will be protected against chafing and wear.

Regardless of the formation of one of the extensions 11 and 12 thicker than the other, or in having both extensions relatively thicker than the portion of the cushion strip overlying the inner side body of the clamp, which is conceivable as within the scope of this invention, the "two-way" and overlapped, extensions 11 and 12 positively prevent the wires from working out of the clamp at the upper corners and from rubbing against the metal body at said corners, and becoming chafed or worn.

If desired, the separate spacer piece 14 vulcanized to the extension 12, may be made of softer material than the cushion proper so as to be compressible readily for accommodating a larger bundle of wires in the clamp than would be the case with a strip of lesser compressibility.

Moreover, such a soft strip will prevent the application of such pressure on the wires as might produce chafing and wear, or deformation thereof.

The flexibility of the strip 14 is increased by forming the flange portions 16 thereof with inwardly beveled outer edges 16, as this formation presents relatively flexible edge portion for contact with the bundle of wires or conduit supported in the clamp.

While the clamp hereof is primarily intended for supporting wires, it is to be understood that it may be used for supporting other lines such as metal conduits, piping, and the like where a cushioned mounting thereof is desired.

I claim:

1. In a cushioned clamp for supporting wires or a conduit, a body member in the form of an open loop for embracing and supporting the wires or conduit, a cushion strip lining the inner surface of said loop, means for mounting the loop on a support; and a pair of extensions on said strip movable into position closing the open side of the loop and so as to lie one upon the other.

2. In a cushioned clamp for supporting wires or a conduit, a body member in the form of an open loop for embracing and supporting the wires or conduit, a cushion strip lining said loop, ears on the ends of said open loop affording the mounting of the loop on a support, and a pair of extensions on said strip formed of cushioning material and arranged to be overlapped and to extend between the ends of the loop so as to enclose the wires or conduits in the open loop.

3. In a cushioned clamp for supporting wires or a conduit, a body member in the form of an open loop for embracing and supporting the wires or conduit, a cushion strip lining the inner surface of said loop, means for mounting the loop on a support; and a pair of extensions on said strip movable into position closing the open side of the loop and so as to lie one upon the other; and means on one of said extensions engaging the other extension so as to hold said extensions against relative movement out of overlapped relation.

4. In a cushioned clamp for supporting wires or a conduit, a body member in the form of an open loop for embracing and supporting the wires on conduit, a cushion strip lining the inner surface of said loop, means for mounting the loop on a support; and a pair of extensions on said strip movable into position closing the open side of the loop and so as to lie one upon the other, one of said extensions being wider than the other.

5. In a cushioned clamp for supporting wires or a conduit, a body member in the form of an open loop for embracing and supporting the wires or conduit, a cushion strip lining the inner surface of said loop, means for mounting the loop on a support; and a pair of extensions on said strip movable into position closing the open side of the loop and so as to lie one upon the other; one of said extensions being wider and thicker than the other extension.

6. In a cushioned clamp for supporting wires or a conduit, a body member in the form of an open loop for embracing and supporting the wires or conduit, a cushion strip lining the inner surface of said loop, means for mounting the loop on a support; and a pair of extensions on said strip movable into position closing the open side of the loop and so as to lie one upon the other; one of said extensions having a groove therein re-

ceiving the other extension to hold the extension in overlapped relation.

7. In a cushioned clamp for supporting wires or a conduit, a body member in the form of an open loop for embracing and supporting the wires or conduit, a cushion strip lining the inner surface of said loop, means for mounting the loop on a support; and a pair of extensions on said strip movable into position closing the open side of the loop and so as to lie one upon the other; an elongated cushion member of channelled form and being of thicker formation than said extensions and vulcanized to one of said extensions and removably receiving the other extension in the channel thereof.
